STOKER

Clifford H. Snyder, Dormont, Pa.

Application January 30, 1941, Serial No. 376,603

21 Claims. (CL 110—45)

This invention relates generally to apparatus for burning solid fuel, such as stokers, and more particularly to novel retort and fire bowl construction for supporting the burning fuel and separating the ash therefrom for removal.

This invention may be conveniently applied to stokers arranged to burn bituminous coal and is particularly adapted to underfed stokers.

In underfed stokers, coal is fed to the retort from below by means of a screw or other conveying or propelling device, and a forced draft is usually applied through the retort to the coal under and into the fire to support and accelerate combustion of the fuel. As the fresh or green coal is fed upwardly through the retort from below, it is preheated by the fire and hot coals thereabove. As this preheating action takes place the gases and other natural products such as oils are driven off and the coal particles become plastic and expand and adhere together, forming pieces of coke materially larger than the original size of the coal particles. The coke is pushed up through the retort and falls to one side where it lays on a horizontal floor around the outer edge of the retort where it burns very sluggishly. This coke is out of the path of the hot part of the fire and often times goes completely dead, in which case it is difficult to re-ignite. At other times considerable partially burning coke accumulates. In either case the coke is not consumed at the proper time to benefit the heating system. This process results in underheating at one period and overheating at another, slow acceleration and deceleration, and waste of fuel.

When bituminous coal is being used in an underfed stoker the ash accumulates at the upper and outer sides of the retort where the heat causes the ash to melt and fuse into clinkers. The clinkers must be removed manually at frequent intervals. The attention required in removing these clinkers from the furnace often largely offsets the advantage of a stoker.

The principal object of this invention is the provision of a method and means for preventing the formation of clinkers within an underfed stoker furnace.

Another object is the provision of novel means for removing the ash from the furnace as it is formed.

Another object is the provision of means for agitating the fuel and crushing partially burned fuel particles so that it is completely burned within a confined and self-contained zone.

Another object is to provide above the ordinary retort an auxiliary retort or container, in which

combustion takes place and through which fine ash is blown and below which heavy ash, slate, etc., is discharged.

Another object is to retain all of the fuel directly above the retort so that during a hold-fire period or during mild weather operation any unburned fuel is held in a zone where it will promptly ignite when the furnace is called upon to produce heat.

10 Another object is the provision of a simple and inexpensive domestic ash removing stoker which is readily adjustable to burn bituminous coals regardless of whether they are high coking or free burning, high or low ash content or high or low ash fusion coals.

15 Another object is the provision of a domestic ash removing bituminous stoker that can be quickly and easily installed as a unit in the smaller domestic furnaces, regardless of their shape and without being assembled integral with the furnace.

Another object is the provision of means for crushing clinkers and large pieces of slate while they are in a hot and friable state.

20 25 Another object is the provision of means for maintaining crushed fuel or coke particles in contact with the hot fuel bed so that they may be consumed before being discharged.

Other objects and advantages appear in the 30 following description and claims directed to the structure of this invention.

In the accompanying drawings a practical embodiment illustrating the principles of this invention is shown wherein:

35 Fig. 1 is a vertical section of a furnace retort comprising this invention.

Fig. 2 is a plan view of the furnace retort shown in Fig. 1.

Fig. 3 is a vertical section of a furnace retort 40 having a rotary fire pot supported thereover.

Fig. 4 is a vertical section of a furnace retort having an adjustable rotary fire pot supported thereover.

Fig. 5 is a plan view of the structure shown in 45 Fig. 4.

Fig. 6 is a detailed isometric view of one of the novel high tuyères shown in Figs. 1 and 4.

Fig. 7 is a view similar to Fig. 6 showing an extended tuyère the upper portion of the face 50 of which slants back at a greater angle than the lower portion.

Fig. 8 is a perspective view of the rotary grate and gear.

Fig. 9 is a plan view of a rotary fire bowl having a specific internal shape.

Fig. 10 is a perspective view of the fire bowl shown in Fig. 9.

Fig. 11 is a vertical section illustrating an underfed stoker retort with the fire bowl illustrated in Figs. 9 and 10 mounted thereon.

Fig. 12 is a top plan view of a modified form of fire bowl.

Fig. 13 is a vertical section of a fire bowl made up of a series of superimposed sections, rotatably supported above a retort.

Referring to Figs. 1 and 2 of the drawings, the reference numeral 10 designates an underfed stoker arranged to be placed in the combustion chamber of a furnace. The stoker 10 comprises a forced draft chamber 11 which surrounds and encloses the lower half of the retort 12 and the fuel feeding passageway 13 connected thereto.

The passageway 13 contains the ordinary screw conveyer 14 for feeding the fuel from a fuel bin or auxiliary hopper to the throat 15 at the lower end of the retort. The interior of the lower section of the retort illustrated is substantially conical, as indicated by the wall 16, and the bottom 17 slopes from the throat 15 at the end of the fuel passage 13 to the opposite wall, as illustrated in Fig. 1. An opening is provided in the bottom 17 for receiving the ring 18 which is provided with a circular bore for permitting the arcuate agitator 19 to reciprocate in the retort.

The agitator 19 is preferably made in arcuate form because it simplifies the structure and operating means. It is shown as being formed integral with the lower end of the arm 20 which is pivoted at 21 and which may be reciprocated by the operating rod 22 pivotally secured to the arm at 23 by means of the bifurcated member 24. When reciprocated the outer end of the agitator extends up through the lower section of the retort into the throat formed by the tuyère blocks as indicated in dotted lines in Fig. 1. This agitator is of circular cross section and displaces a considerable amount of coal and coke particles through the axis of the retort throat.

The inner faces of the tuyères, which make up the upper portion of the retort, continue the upwardly expanding conical throat of the lower retort section. There are two types of tuyère blocks shown, the low tuyères 25 and the high tuyères 26. The low tuyères 25 represent the ordinary tuyères known in the art. They are hollow and receive air from the chamber 11 and discharge it in a downward direction into the throat of the retort, and they are provided with hooked shaped members for locking them into position on the lower section of the retort.

The tuyère blocks 26 are preferably constructed so that they extend materially above the top of the other tuyères and are not as wide as the ordinary tuyère block. The inner sloping faces of these tuyères are provided with openings for directing air into the center of the retort. This tuyère block is shown in detail in Fig. 6 which shows openings in the sides 26a and bottom 26b between the two integrally formed hook members 26c. A shoulder 27 is formed on the rear of these tuyères for supporting the annular stationary grate ring 28. A threaded opening 29 is provided in the shoulder 27 for receiving the bolts 30 which pass through the arcuately disposed grate slots 31 for securing the grate ring to the retort.

The grate may be made in one piece, in which case it also acts to hold the tuyère blocks in assembled relation, otherwise a tuyère block clamp-

ing band 32 is required. The clamping band is made up of a split band having outwardly extending ears which are bolted together.

The grate slots 31 become wider toward the under side of the grate ring to prevent small fuel or clinker particles from being caught therein.

It should be noted that the top surface of the grate ring 28 is flush with the top of the tuyère blocks 25.

A ring gear 33 is rotatably mounted on the retort in any suitable manner such as by the annular race bearing 34 which in turn is supported on spaced legs 35 disposed around the outer shell 15 of the retort. Teeth 36 are formed on the perimetral edge of the gear 33. These teeth have a radially disposed face which is engaged by the screw 37 for driving the same. A plurality of spaced upwardly extending braces 38 are welded or otherwise secured at their lower ends to the top surface of the gear 33 and at their upper ends to the annular rotary grate 40. The rotary grate is provided with a series of arcuate grate slots 41 the opening of which increases toward the under surface of the rotary grate which lies in the same plane as the stationary gate ring 28 but is concentrically spaced therefrom, as illustrated on the drawings. The ring gear and the rotary grate are also illustrated in Fig. 8.

30 The screw 37 lies in the same horizontal plane as the gear 33 and is arranged when driven to rotate the gear and the grate ring and to convey the ashes out of the furnace away from the retort. The rotary movement of the grate and the gear carry the ashes around to the side where the screw 37 is located. The cover of the conduit 32 which encloses the screw 37 stops short of the retort to provide ample room for driving the gear 33 and for picking up the ash.

35 40 The high tuyère blocks 26 prevent coke formation from dropping off to one side of the retort where it may burn when heat is not required or where it may lay dormant until the accumulation is such that it must be removed manually. These high tuyères hold the coke above the fuel bed and it is thus consumed at the proper time. Conditions producing coke formations of such size may occur during long off periods when the agitator is not operating and the fuel burns deep into the retort.

45 50 When the agitator is reciprocated frequently it churns and moves the coke particles, preventing the formation of large masses of coke.

55 60 When the retort is operated at frequent intervals and the small particles of fuel, which are still burning, are spilled out between the high tuyères they are held on the grate ring where they may finish burning and the ash thereof is finally deposited on the screw 37.

65 70 The high tuyères are equipped with openings for discharging air toward the vertical axis of the retort. Thus when the fuel bed is above the ordinary tuyères 25 it is supplied with an additional amount of air to support combustion. The forced draft from the high tuyères induces the movement of air and gases from around the retort into the center thereof, which materially aids in supporting proper combustion at the precise time that it is needed to produce heat and also ignites any unburned gases before they pass to the flue. This novel improvement forms an important object of this invention.

75 The high tuyère 49 shown in Fig. 7 is similar to the high tuyère 26 except that the upper por-

tion 44 of its face recedes or slopes at a greater angle to the vertical than the lower portion 45 which has the same slope as the faces on the ordinary tuyères 25. The reason for setting the upper face portion 44 farther from the vertical axis of the retort is to get it farther away from the center of the fire which is normally the hottest part of the fire and further to permit greater expansion of the fuel bed at this particular level. The tuyères 26 and 43 are of course interchangeable.

Again it is advantageous to use the tuyères 43, the faces of which have different angular slopes, to aid the movement of the ash and fuel particles making up the top fire bed. The agitator 19 raises and lowers or otherwise causes the fuel particles to spread, churn and move over the top of the fire bed. The movement of the fuel particles induced by the movement of the agitator is referred to as "breathing." It is obvious that the breathing action of the fuel particles against different degrees of the sloping faces of the tuyères produces a desired predetermined movement of these fuel particles around and through the bed, and a body of looser fuel extending over a greater area.

In Fig. 3 an ordinary set of tuyère blocks 25 is shown. The ring gear 33 in this structure merely rests on the shelf 46 of the forced draft housing of the retort. A flat graphite ring 47 may be placed on the shelf 46 and a graphite collar 48 may be placed around the tuyère blocks to reduce the friction of the gear ring 33.

The upwardly extending posts 49 are secured at their lower ends to the ring gear 33 and are arranged to support the fire bowl 50. This fire bowl may be made of any suitable heat resistant metal or ceramic. It is preferably in the shape of an inverted frustum of a cone, the smallest diameter of which is at least as great and preferably greater than the diameter of the bell end of the retort. The fire bowl may be made in one or more pieces. When it is constructed from a ceramic material indented pockets may be formed on the perimetral surface for receiving the upper ends of the posts 49.

The fire bowl 50 being supported on the ring gear 33 thus rotates with the same and its lower rim is preferably spaced sufficiently above the tuyère blocks 25 as indicated by the annular opening 51 to prevent the escape of a fair sized piece of fuel. However the relative motion of the fuel particles created by the agitator and the rotating bowl tumbles the ash downwardly and permits it to be discharged radially outwardly through the opening 51 where it is picked up by the ring gear 33 and carried to a suitable ash pit or bin at the side of the retort or to an ash removing screw as illustrated in Fig. 2.

The fine ash that is sufficiently light to be carried by the forced draft up through the burning fuel in the fire bowl passes out the flue or is precipitated to the side of the retort.

The forced draft which is discharged through the tuyère openings into the throat of the retort travels upwardly through the fire bowl. This draft of air up through the fire bowl draws gases and air from the combustion chamber in through the annular opening 51 which burns and aids in supporting the combustion of the fuel at the opening. This circulation of air within the combustion chamber is in the shape of an annular vortex, thereby burning a greater percent of the gases which ordinarily pass out through the chimney.

Figs. 4 and 5 show the fire bowl 50 being supported by the threaded posts 52 secured to the brackets 53 welded to or formed integral with the rotary grate 40. Thus the high tuyères 26 and the rotary grate structure shown in Figs. 1 and 2 are employed with the fire bowl 50. It will be noted that the high tuyères 26 are not uniformly positioned about the axis of the retort in Fig. 5 but are grouped around the upper side. 10 The reason for placing these tuyère blocks in this manner is to counteract the feeding effect of the screw 14 as it tends to pile the fuel up on this side.

The fire bowl 50 shown in Figs. 4 and 5 is provided with three pocket recesses 54 having opposed bifurcated lugs 55 arranged to receive the narrow neck of the adjusting sleeve 56. These sleeves are each provided with a threaded bore which enables them to be raised and lowered on the threaded post 52. Since the bowl is provided with a three point suspension it may be readily adjusted thereon as illustrated in full and dotted lines in Fig. 4. By adjusting one side of the bowl higher above the stationary grate 28 than the other, the lower rim becomes spaced further from the high tuyère 26 on one side than on the other. Such an adjustment permits the bowl 50 to be rotated on an eccentric path relative to the vertical axis of the retort. If the eccentricity is not great enough the lugs 55 may be positioned at different elevations on the bowl to render the bowl eccentric or tipped to the axis of the retort. Thus the rotary movement of the bowl through an inverted conical orbit, such as is attainable with the adjustment shown in Fig. 4, results in the crushing of the fuel particles between the lower rim of the bowl and the stationary grate 28 and between the lower inner surface of the bowl and the backs and sides of the high tuyères.

Because of the eccentric relation of the bowl to the high tuyères as the bowl is being rotated it squeezes the fuel or clinkers while in a friable state between the inner wall and the sides and back of each high tuyère. The pieces crushed in this manner are then held by the stationary grate 28 and rotary grate 40 in direct contact with the fire for considerable time. If these crushed particles are combustible they are consumed, but if the particles crushed are clinkers they cannot again re-fuse because while the fire supported on the grates 28 and 40 is hot enough to consume fuel the heat is not sufficiently intense to melt ash or clinker. Re-fusing of the ash or clinker is also prevented because no depth or quantity of same can accumulate on the grates. These are novel features of this invention. After considerable time the ash and clinkers work through the slots 31 and 41 and between the stationary grate 28 and the rotary grate 40. If the particles which are crushed in this manner are fuel they will be more readily burned at the time when the heat is most needed, and if the particles are ash or clinkers they will be crushed and discharged out from under the bowl onto the grate where they are carried to the ash pit containing the ash conveyor screw.

Thus the combined action of the agitator and the rotary, eccentrically disposed bowl promote agitation and subsequent crushing of the fuel as it is being discharged radially outwardly from a zone intermediate of the height of the fire bed supported in the retort and the rotary fire bowl.

One advantage of having a rotary fire bowl 75 above the retort is in the radial discharge of

the fuel and ash particles mechanically from this intermediate zone of the fire bed which is produced by this relative rotary movement. In most retorts the ash and fuel particles are permitted to spill out over the top of the retort. With this structure the ashes and fuel particles are not discharged over the top of the bowl and a positive motion is mechanically imparted to the ash and fuel particles which reach this zone, crushing them and forcing them to be discharged radially outwardly under the bowl in the face of an induced draft of gas and air from the combustion chamber which further and quickly supports combustion of the fuel particles.

When the vertical and horizontal crushing action is added to this structure the action is made more positive and the combustion speeded up at the proper time, preventing overheating, because partially burned coked fuel is not permitted to accumulate and burn when the furnace is not operating.

In Figs. 9, 10 and 11 a different type of fire bowl 50 is shown. Here the fire bowl is made up in three sections 55, each section being made from the same pattern and each providing an inner arcuate surface 56 which is disposed eccentrically to the axis of the bowl at the lower end and tapering off to a common concentric rim 57 at the top. These sections may be made of metal, a ceramic, or metal lined with a ceramic.

One end of each section 55 is provided with the spaced eyes 58 and 59 and the other end with the spaced eyes 60 and 61 disposed at different heights than the spaced eyes 58 and 59. When the three sections are placed in assembled relation to form the bowl the spaced eyes on the adjacent ends become interleaved with the eyes in vertical alignment. The bowl is held in this alignment and the eyes are threaded down over the studs or posts 52 as shown in Fig. 11. A shoulder 62 may be provided on the studs 52 for limiting the downward movement of the bowl on the three studs. This shoulder may be formed integral with the stud or the rotary grate ring or it may be produced by the use of a collar slid down over the studs, as shown at 62 in Fig. 11. The bowl 50 is locked in place by the nuts 64 threadably secured on the upper ends of the studs 52. The fire bowl may be adjustably supported as shown in Figs. 4 and 5.

As shown in the drawings the upper rim of this bowl is concentric to its own axis which is coincident with the axis of the retort. However the inner arcuate surfaces 56 are eccentrically disposed to the high tuyères 26 which are positioned concentrically around the retort.

The bowl is arranged for rotation in a clockwise direction when viewed from above. Thus the leading end of the eccentric surface is spaced a greater distance from the backs of the high tuyères than the trailing end. The pockets or voids formed by these eccentric surfaces thus become gradually smaller as the bowl rotates, and any clinker or fuel particles that cannot pass between the high tuyère and the bowl are either crushed or moved inwardly toward the center of the fire in the bowl.

In view of the fact that the eccentric surfaces 56 are also conical there is a tendency for the fuel particles to be raised by the rolling action up along the surface of the bowl. The higher up the surface the greater the gap between the bowl and the backs of the high tuyères. However the climbing action of the fuel particles is interrupted by the sudden offset created by the abrupt

recesses produced by these eccentric arcuate surfaces. The fuel particles are thus rolled and tend to climb each arcuate wall surface until the particles reach the end where the surface drops back to the next succeeding arcuate surface, and then the particles are dropped.

Only the large aggregates are crushed since the smaller particles either pass through the gap, are raised or moved into the center of the fire.

10 The movement of the agitator accentuates the movement of the fuel particles, and the movement of the fuel particles promotes quick combustion at the time when heat is required. The movement of the fuel particles also induces the sifting 15 of the ash down through the bowl to the grate where it is discharged. The fine ash is blown out of the bowl by the forced draft. This is readily accomplished because the particles of fuel are kept loosely churning in the fire bowl and 20 the air traveling upwardly therethrough picks up the fine ash and carries it along.

In the structure shown in Fig. 11 the ring gear 33 is rotatably supported by the conical rollers 65 carried by the spaced radially disposed stub shafts 66.

When a plain frusto conical bowl, such as that shown in Fig. 3, is rotatably supported above a retort having high tuyères 26, an opening 67 may be provided adjacent the lower edge of the bowl 30 for receiving large pieces of coke or clinkers. As the bowl rotates these pieces of coke or clinker are crushed against the sides of the high tuyères and left exposed to the fire where they are burned or continue to be ground up to permit their discharge through the opening 61.

In Fig. 12 the frusto conical fire bowl 50 is provided with a series of inwardly projecting ribs 68 which may be formed integral with the bowl or welded thereto. The sides of these ribs act 40 in the same manner as the opening 67 or inwardly projecting portions of the bowl shown in Figs. 9, 10 and 11, in crushing the coke and clinker particles against the high tuyères. Bowl structures of this character need not be placed eccentrically of the retort to produce the desired result.

The fire bowl structure shown in Fig. 13 is made up of a series of frusto conical bowl sections 70, 71 and 72 welded or otherwise secured to the spaced standards 73 fixed at their lower ends to the top surface of the rotary grate 40 and disposed so that the bowls are eccentric to the vertical axis of the retort. The diameter of each bowl section increases from the bottom to the top. 55 Thus as the burning fuel rises in the bowl sections the fire radiates from between them. However the diameter of the lower bowl section 70 is materially greater than the outside diameter of the high tuyères 26.

60 By making each upper bowl section greater in diameter the fire is not permitted to burn against the under side of the bowl sections. The bowl sections are spaced relatively close together and the large coke or clinker particles cannot pass 65 therebetween but work down to the lower section and become crushed against the high tuyères by the eccentric movement of the bowl sections.

During operation the green coal is fed to the retort by the coal feed screw, which is rotated 70 by external means. A forced draft of air is fed into the retort through its inner walls. The agitating mechanism is arranged to be alternately inserted into the retort. The fire bowl is preferably located at a distance of approximately one-half inch to one inch above the outer edge of the

tuyères in the retort and is mounted on the gear 33. This gear is rotated by the ash removing screw which is driven by the same means that operates the feed screw. Thus the fire bowl is constantly rotated as the stoker is operated and the agitator is inserted into and withdrawn from the fuel in the retort at the same time.

As the coal is moved upward it is preheated and coked. The burning fuel is pushed vertically out of the top of the retort into the fire bowl 10 by the new green coal fed from below. The burning fuel is thus held above the retort in the fire bowl.

Because of the positive agitation which the fuel receives both in the retort and at all points in 15 the fire bowl, a shallow fuel bed is constantly maintained. No fuel goes over the top of the fire bowl. The fuel is burned as fast as it is fed and at the time heat is desired. During the off period coke in the fire bowl quickly decelerates, but since it is held directly over the retort it ignites almost instantly when the stoker comes on. Thus all the fuel is kept under control at all times, which results in control of combustion of coal not heretofore obtainable and which approaches the on and off control of the combustion of liquid and gaseous fuels.

The alternate insertion into and withdrawal of the agitator from the retort causes a raising and lowering or breathing of the fuel in the retort and in the fire bowl. A forced draft of air blows the light ash up through and out of the fire bowl and into the combustion chamber of the furnace around the outside edge of the retort. The vertical action of the retort agitator, which raises and lowers all the fuel by displacement, combined with the rotary action of the fire bowl, causes a separation of the ash from the fuel as well as to maintain a loose uniform fire. At the same time, the displacement caused by the insertion of the agitator into the fuel causes a slight pressure of the fuel particles against the sides of the retort and sides of the fire bowl. This latter action pushes the ash out into the annular opening between the retort and the fire bowl. Any large pieces of slate or other material is crushed between the fire bowl and the tuyères. The ash moves radially outwardly over the grates and the gear, which carries it around to the ash remover screw. The ash remover screw then conveys the ash from the furnace.

I claim:

1. In a retort of an underfed stoker of the character described, the combination of a retort section having an annular series of low tuyère blocks of uniform height producing an upwardly flaring wall forming a throat and arranged to receive fuel at the bottom, and a plurality of high tuyère blocks interposed between and extending materially above the low tuyère blocks to support and confine the fuel above the throat of the retort, said high tuyère blocks having openings on their inner face for directing a forced draft toward the center of the fuel thus confined, the inner faces of said high tuyère blocks forming an upward continuation of the wall of the said retort section,

2. In a retort of an underfed stoker of the character described, the combination of a retort section having an annular series of low tuyère blocks of uniform height producing an upwardly flaring wall forming a throat and arranged to receive fuel at the bottom, a plurality of high tuyère blocks interposed between and extending materially above the low tuyère blocks to support and con-

fine the fuel above the throat of the retort, said high tuyère blocks having openings on their inner face for directing a forced draft toward the center of the fuel thus confined, the inner faces of said high tuyère blocks forming an upward continuation of the wall of the said retort section, a grate ring surrounding the tuyère blocks, and means for supporting the grate ring with its upper surface substantially flush with the tops of the low tuyère blocks.

3. In a retort of an underfed stoker of the character described, the combination of a retort section having an annular series of low tuyère blocks of uniform height producing an upwardly flaring wall forming a throat and arranged to receive fuel at the bottom, a plurality of high tuyère blocks interposed between and extending materially above the low tuyère blocks to support and confine the fuel above the throat of the retort, 10 said high tuyère blocks having openings on their inner face for directing a forced draft toward the center of the fuel thus confined, the inner faces of said high tuyère blocks forming an upward continuation of the wall of the said retort section, a grate ring surrounding the tuyère blocks and supported for rotation with its upper surface substantially flush with the tops of the low tuyère blocks, and means for rotating the grate ring.

4. In a retort of an underfed stoker of the character described, the combination of a retort section having an annular series of low tuyère blocks of uniform height producing an upwardly flaring wall forming a throat and arranged to receive fuel at the bottom, a plurality of high tuyère blocks interposed between and extending materially above the low tuyère blocks to support and confine the fuel above the throat of the retort, 20 said high tuyère blocks having openings on their inner face for directing a forced draft toward the center of the fuel thus confined, the inner faces of said high tuyère blocks forming an upward continuation of the wall of the said retort section, a grate ring surrounding the tuyère blocks and supported for rotation with its upper surface substantially flush with the tops of the low tuyère blocks, and means for rotating the grate ring.

5. In an underfed stoker of the character described, the combination of a retort section having an upwardly flaring wall forming an enclosed throat and arranged for receiving fuel at the bottom, an annular series of low tuyère blocks of uniform height supported by said retort section, a plurality of high tuyère blocks interposed between the low tuyère blocks, the inner faces of all of said tuyère blocks forming an upward continuation of the wall of the said retort section, and an auxiliary open bottom continuous annular fire bowl the internal diameter of which is at least 25 as great as that of the upper end of the retort, and means for supporting the auxiliary fire bowl relative to the low tuyères and surrounding the high tuyères to provide an annular gap for the induction of air and the discharge of ash between the auxiliary fire bowl and the retort.

6. In an underfed stoker of the character described, the combination of a retort section having an upwardly flaring wall forming an enclosed throat and arranged for receiving fuel at the bottom, an annular series of low tuyère blocks of uniform height supported by said retort section, a plurality of high tuyère blocks interposed between the low tuyère blocks, the inner faces of all of said tuyère blocks forming an upward continuation of the wall of the said retort section, an

auxiliary open bottom continuous annular fire bowl the internal diameter of which is at least as great as that of the upper end of the retort, and means for supporting the auxiliary fire bowl relative to the low tuyères and surrounding the high tuyères to provide an annular gap for the induction of air and the discharge of ash between the auxiliary fire bowl and the retort, and means to rotate the auxiliary fire bowl.

7. In an underfed stoker of the character described, the combination with a vertically disposed retort having an upwardly flaring wall and means for introducing fuel at the bottom of the retort, of an auxiliary open bottom fire bowl the internal diameter of which is at least as great as that of the upper end of the retort, means for supporting the fire bowl in close proximity to the retort for receiving and holding burning fuel from the throat of the retort and to provide an annular gap between the auxiliary fire bowl and the retort, and means to rotate the fire bowl, the axis of the fire bowl being tilted relative to the axis of its rotation.

8. In an underfed stoker of the character described, the combination of a retort section having an upwardly flaring wall forming an enclosed throat and arranged for receiving fuel at the bottom, an annular series of low tuyère blocks of uniform height supported by said retort section, a plurality of high tuyère blocks interposed between the low tuyère blocks, the inner faces of all of said tuyère blocks forming an upward continuation of the wall of the said retort section, an auxiliary open bottom fire bowl the internal diameter of which is at least as great as that of the upper end of the retort, and means for supporting the auxiliary fire bowl relative to the low tuyères and surrounding the high tuyères to receive and hold the burning fuel from the throat of the retort and to provide a gap between the auxiliary fire bowl and the tuyères, said supporting means holding the auxiliary fire bowl with its axis tilted relative to the axis of the throat, and means to rotate the fire bowl.

9. In an underfed stoker of the character described, the combination of a retort section having an upwardly flaring wall forming an enclosed throat and arranged for receiving fuel at the bottom, an annular series of low tuyère blocks of uniform height supported by said retort section, a plurality of high tuyère blocks interposed between the low tuyère blocks, the inner faces of all of said tuyère blocks forming an upward continuation of the wall of the said retort section, an auxiliary open bottom fire bowl the internal diameter of which is at least as great as that of the upper end of the retort, and means for supporting the auxiliary fire bowl to surround the high tuyères, means to rotate the auxiliary fire bowl, and an internal surface on said fire bowl arranged to coat with the high tuyères for crushing large fuel and clinker particles between them.

10. In an underfed stoker of the character described, the combination of a retort section having an upwardly flaring wall forming an enclosed throat and arranged for receiving fuel at the bottom, an annular series of low tuyère blocks of uniform height supported by said retort section, a plurality of high tuyère blocks interposed between the low tuyère blocks, the inner faces of all of said tuyère blocks forming an upward continuation of the wall of the said retort section, an auxiliary open bottom fire bowl the internal diameter of which is at least as great as that of the upper end of the retort, and means for support-

ing the auxiliary fire bowl to surround the high tuyères, means to rotate the auxiliary fire bowl, and a plurality of internal annularly arranged surfaces in the fire bowl angularly disposed to the axis of the retort and arranged to coat with the high tuyères for crushing large fuel and clinker particles between them.

11. In an underfed stoker of the character described, the combination of a retort section having

10 an upwardly flaring wall forming an enclosed throat and arranged for receiving fuel at the bottom, an annular series of low tuyère blocks of uniform height supported by said retort section, a plurality of high tuyère blocks interposed between the low tuyère blocks, the inner faces of all of said tuyère blocks forming an upward continuation of the wall of the said retort section, a frusto conical fire bowl disposed above the retort and into which the high tuyères extend, means to support the fire bowl tilted relative to the axis of the retort, and means for rotating the fire bowl.

12. In a retort of an underfed stoker of the character described, the combination of a retort section having an upwardly flaring wall forming an enclosed

25 throat and arranged for receiving fuel at the bottom, an annular series of low tuyère blocks of uniform height supported by said retort section, a plurality of high tuyère blocks interposed between the low tuyère blocks, the inner faces of all of said tuyère blocks forming an upward continuation of the wall of the said retort section, a grate ring surrounding the tuyère blocks and fixed relative thereto, a second grate ring concentric with and spaced outwardly from the first grate ring, a frusto conical fire bowl supported by the second grate ring and disposed above the first grate ring and into which the high tuyères extend, the axis of the fire bowl being tilted relative to the axis of the retort, and means for rotatably supporting the second grate ring.

13. In an underfed stoker of the character described comprising a retort having an upwardly flaring wall forming an enclosed throat and ar-

25 ranged for receiving fuel at the bottom, an annular series of spaced apart projections around the top of the retort extending materially thereabove to support and confine the fuel above the throat of the retort, the inner face of the projections forming a continuation of the throat, and spaced openings through the wall of the inner face of the upper portion of the retort and of the projections to direct air for supporting combustion of the fuel retained by the retort and projections.

14. In an underfed stoker of the character de-

25 scribed, the combination with a vertically disposed retort having an upwardly flaring wall forming an enclosed throat and arranged for receiving fuel at the bottom, of a continuous annular fire bowl the internal diameter of which is at least as great as that of the upper end of the throat of the retort, means for supporting the fire bowl in close proximity and in spaced relation with the retort to receive and hold burning fuel from the throat of the retort and to provide an annular gap therebetween, the axis of the fire bowl being out of alignment with the axis of the throat of the retort, and means for rotating the fire bowl.

15. In an underfed stoker of the character de-

25 scribed for installation in a furnace, the combination with a vertically disposed retort having an upwardly flaring wall forming an enclosed throat and arranged for receiving fuel at the bottom, of an auxiliary continuous annular fire bowl, means for rotatably supporting the auxiliary fire bowl in

close proximity to the retort to receive and hold the burning fuel from the throat thereof, means for rotating the auxiliary fire bowl, and means for adjusting the proximity of the fire bowl to the retort.

16. In an underfed stoker of the character described for installation in a furnace, the combination with a vertically disposed retort having an upwardly flaring wall forming an enclosed throat and arranged for receiving fuel at the bottom, of an auxiliary continuous annular fire bowl, means for rotatably supporting the auxiliary fire bowl in close proximity to the retort, from three points which are independently adjustable to receive and hold the burning fuel from the throat thereof, and means for rotating said auxiliary fire bowl.

17. In an underfed stoker of the character described for installation in a furnace, the combination with a vertically disposed retort having an upwardly flaring wall forming an enclosed throat and arranged for receiving fuel at the bottom, of an open ended continuous annular auxiliary fire bowl having its lower end circumventing the upper end of the retort, a grate structure interposed between the retort and the fire bowl forming a floor for the latter, and means for rotatably supporting the fire bowl.

18. In an underfed stoker of the character described for installation within a furnace chamber, the combination with a vertically disposed retort having an upwardly flaring wall and means for introducing fuel at the bottom of the retort, of an auxiliary open bottom continuous annular fire bowl the internal diameter of which is at least as great as that of the upper end of the retort, the upwardly extending wall of the auxiliary fire bowl being of sufficient height to receive and hold in confinement substantially all of the burning fuel discharged from the retort until combustion is completed, and means for supporting the auxiliary fire bowl in close proximity to the retort to provide an annular gap between the fire bowl and the retort for the discharge of all of the ash from the fuel bed.

19. In an underfed stoker of the character described for installation within a furnace chamber, the combination with a vertically disposed retort having an upwardly flaring wall and means for introducing fuel at the bottom of the retort, of

5 an auxiliary open bottom continuous annular fire bowl the internal diameter of which is at least as great as that of the upper end of the retort, the upwardly extending wall of the auxiliary fire bowl is of sufficient height to receive and hold in confinement substantially all of the burning fuel discharged from the retort until combustion is completed, means for supporting the auxiliary fire bowl in close proximity to the retort to provide an annular gap between the fire bowl and the retort for the discharge of all of the ash from the fuel bed, and means to rotate the auxiliary fire bowl to agitate the burning fuel and to facilitate the discharge of the ash.
